(57) **CLAIM**

The ornamental design for a meat grinder, as shown and described.

DESCRIPTION

FIG. 1 is a front perspective view of a meat grinder, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front perspective view thereof, shown in open condition; and,

FIG. 10 is a partially enlarged view thereof, taken from FIG. 1.

The broken lines in the drawings illustrate the portions of the meat grinder, which form no part of the claimed design. The dot-dash broken lines in FIGS. 1 and 10 are included to show the partially enlarged views only and form no part of the claimed design.

1 Claim, 10 Drawing Sheets
